UNITED STATES PATENT OFFICE.

JAMES L. HEROLD, OF ST. LOUIS, MISSOURI, ASSIGNOR TO BARRY-WEHMILLER MACHINERY COMPANY, OF ST. LOUIS, MISSOURI, A CORPORATION OF MISSOURI.

TEMPERATURE-CHANGING APPARATUS.

Application filed January 28, 1926. Serial No. 84,527.

This invention relates generally to temperature-changing apparatus, and particularly to an apparatus adapted to gradually change the temperature of articles which are caused to pass through said apparatus.

My improved apparatus is capable of being used where it is desired to gradually increase or decrease the temperature of the articles passing through the apparatus, but to illustrate one embodiment of the invention I show in the drawings and describe in the specification an apparatus for gradually cooling bottles, for instance, milk bottles. As is well known, bottles such as milk or soda bottles, or, in fact, most bottles in which goods are marked, are returned to the sellers after being emptied by the buyers and are cleaned, sterilized and refilled and are again sent out to the trade. In the operation of cleaning and sterilizing the bottles extremely hot water is used, and it is necessary in the cases where relatively cold liquid is marketed in the bottles that said bottles be gradually cooled to prevent the cracking thereof when the liquid is placed in the bottles immediately after the cleaning and sterilizing operations.

My improved apparatus provides means whereby bottles may be gradually cooled so that they may be filled with comparatively cold liquid without the loss of time necessary to permit said bottles to be cooled by the atmosphere after being washed and sterilized, and briefly stated, the apparatus comprises a housing through which the bottles or other articles are passed. Arranged within the housing mentioned are elongated water receptacles, said water receptacles being so arranged that the articles passing through the housing of the apparatus move longitudinally of said water receptacles. The arrangement of the water receptacles is such that a plurality of streams of water of different temperatures are introduced into said water receptacles, and certain of said streams of water are caused to merge to provide elongated bodies of water the temperature of which gradually varies as successive temperature readings are taken in a direction longitudinal of said bodies of water. The water receptacles are provided with discharge apertures which are so arranged that as the ar-

ticles pass longitudinally of the water receptacles they encounter successive showers of water, and due to the fact that the water comprising each successive shower of water is of a different temperature from the preceding shower of water, said articles will be gradually cooled or heated, as the case may be, as they pass through the apparatus.

With the foregoing and other objects in view, the invention comprises the novel construction, combination and arrangement of parts hereinafter more specifically described and illustrated in the accompanying drawings, wherein is shown the preferred embodiment of the invention. However, it is to be understood that the invention comprehends changes, variations and modifications which come within the scope of the claims hereunto appended.

Fig. I is a vertical section through an apparatus constructed in accordance with my invention.

Fig. II is a perspective of the water receptacles comprising parts of my improved apparatus.

Fig. III is an enlarged fragmentary vertical section showing the means for discharging water from a single conductor into a pair of water receptacles.

Fig. IV is a fragmentary cross section of the apparatus on line IV—IV of Fig. I showing the arrangement of the bottle holders with respect to the water receptacles.

To illustrate one of the uses of my invention, I have shown a bottle-cooling apparatus in the drawings, said apparatus comprising an endless bottle carrier traveling through a housing A. The bottle carrier comprises a pair of endless flexible traveling supports, preferably sprocket chains B located at the opposite sides of the apparatus, and a series of bottle holders C. The bottle holders C are preferably arranged in units comprising each a transverse row of bottle holders, and the opposite ends of each of said units are secured to the oppositely disposed sprocket chains, as shown in Fig. IV. Also, said units are so arranged with respect to each other that rows of bottle holders are provided, which are arranged longitudinally of the housing A of the apparatus. Each of the sprocket chains B operates over a

sprocket wheel D and a plurality of smooth guide wheels E, said sprocket wheels and guide wheels being so located that the bottle holders travel over an angular course within the housing A, as shown in Fig. I. The housing A is supported by a plurality of supporting elements F which rest upon the floor. By referring to Fig. I it will be noted that the bottle holders C are so shaped that the bottles enter said bottle holders mouth end foremost, and when said bottles are traveling adjacent to the top wall of the housing they are inverted.

G designates a suitable bottle-conveying device by means of which bottles are introduced into the apparatus, said bottle-conveying device being so arranged that rows of bottles are introduced mouth-end foremost into the transverse rows of bottle holders. The bottle holders C travel in the direction indicated by the arrow in Fig. I, and when the bottles have passed through the apparatus and arrive at the opposite end thereof they are discharged from the bottle holders onto an inclined receiving member H provided with a pivoted portion H' adapted to be operated to deposit the bottles in an upright position on an endless conveyor J by means of which said bottles are conveyed away from the apparatus.

Arranged within the housing A is an elongated tank 1, said tank being so arranged that the bottle holders travel entirely around said tank. The tank 1 is provided with a plurality of partitions 2 which divide said tank into several compartments, said compartments being designated in Fig. I by the reference characters 3, 4, 5 and 6. By referring to Fig. I it will be noted that an end wall of the compartment 6 is inclined, said end wall being approximately parallel with the adjacent portions of the sprocket chains B. By referring to Fig. I it will be noted that the partition 2 between the compartments 5 and 6 and the partition 2 between the compartments 4 and 5 are each provided with an overflow aperture 7, while the partition between the compartments 3 and 4 is not provided with such an aperture. The compartments 3, 4, 5 and 6 are distinct from each other and are fluid-tight, and as a result liquid in the compartment 6 may pass into the compartment 5 only through the overflow aperture 7 in the partition which divides said compartments, and liquid in the compartment 5 may pass into the compartment 4 only through the overflow aperture 7 in the partition which divides the last mentioned compartments. Due to the absence of an overflow aperture in the partition which divides the compartments 3 and 4 the liquid within said compartment 4 will not find its way into the compartment 3.

8 designates a steam pipe which is ar-

ranged transversely of the compartment 3. The portion of the steam pipe which is arranged within the compartment 3 is perforated and steam is passed through said pipe from a suitable source and escapes into the compartment 3 through the apertures in said pipe. The steam pipe 8 is provided with a thermostatically controlled valve 9 of any suitable construction, which is adapted to function so that when the temperature of the liquid within the compartment 3 drops below a predetermined point the valve 9 will be opened and steam will be introduced into said liquid, whereby the temperature thereof will be increased. When the temperature of the liquid within the compartment 3 has reached the predetermined point, the valve 9 will be automatically closed by the thermostatic device associated therewith and the discharge of steam from the pipe 8 will be stopped. Thermostatic devices of the type associated with the valve 9 of my apparatus are very well known and may be purchased on the market, and therefore it is not thought to be necessary to describe same in detail, all that need be known being that a portion of the device which is sensitive to changes in temperature is extended through a wall of the compartment and into the liquid within said compartment.

When the temperature of the liquid within said compartment changes the change is felt by the portion of the thermostatic device which extends into said liquid, and when the change has become great enough the valve will be operated to either permit or prevent the escape of steam into the compartment. It is apparent, therefore, that my apparatus includes means whereby the temperature of the liquid within the compartment 3 is maintained approximately uniform at all times.

Arranged within the compartment 4 is a steam pipe 10 provided with perforations through which steam may escape into said compartment. The compartment 4, like the compartment 3, contains a body of liquid, and the steam pipe has associated with it a thermostatically controlled valve 11 whereby the discharge of steam from said pipe 10 may be automatically controlled. A portion of the thermostatic device extends through a wall of the compartment 4 and into the liquid within said compartment so that when the temperature of the liquid within the compartment changes sufficiently the valve 11 will be operated to permit or prevent the discharge of steam into the liquid within the compartment whereby the temperature of said liquid is maintained approximately uniform at all times.

Arranged within the compartment 5 is a steam pipe 12 provided with perforations, and arranged within the compartment 6 is a perforated steam pipe 13. The steam pipes

12 and 13 are not provided with thermostatically controlled valves for automatically regulating the admission of steam into the compartments 5 and 6, but said steam pipes 5 are merely provided with ordinary manually operated valves, the reason for this being, as will appear later herein, that it is only necessary to introduce steam into the compartments 5 and 6 when the apparatus is 10 being started up. After the apparatus is in operation the temperatures of the liquid within the compartments 5 and 6 are maintained approximately uniform.

14 designates a plurality of conductors arranged transversely of the housing A adjacent to the intake end of the apparatus, said conductors being supported in any suitable manner and being spaced to correspond to the spacing of the bottle holders in a direction longitudinally of the apparatus. Extended upwardly from each of the conductors 14 is a plurality of injectors 15. The injectors 15 are spaced longitudinally of the conductors 14 and transversely of the housing A, the spacing of said injectors being the same as the transverse spacing of the bottle holders and the passageways through said injectors being in communication with the interiors of the conductors. P designates a pump, preferably a 3-stage pressure pump, said pump being provided with an inlet pipe 16 which is extended through a wall of the compartment 3 and into said compartment, the open end of said inlet pipe within the compartment being provided with a suitable screen to prevent the passage therethrough of solid matter. Also, the pump P is provided with a discharge pipe 17 leading to a head 18. 19 designates a plurality of conductors which place the interiors of the conductors 14 in communication with the interior of the head 18. In the operation of the apparatus water from within the compartment 3 is drawn from said compartment by the pump P, said water being placed under pressure by said pump and being forced through the discharge pipe 17, head 18, conductors 19 and 14 to the injectors 15, from which said water is injected forcibly into the bottles located above said injectors whereby the interiors of said bottles are washed.

20 designates a pair of conductors arranged transversely of the apparatus below adjacent transverse rows of bottle holders. Extended upwardly from each of the conductors 20 is a plurality of injectors 21, the spacing of said injectors 21 transversely of the apparatus corresponding to the spacing of the bottle holders in that direction. 22 designates a conductor which is in communication with the conductors 20. Very hot water is conducted from a suitable source of supply, for instance, from a boiler, by 25 the conductor 22 to the conductors 20, and

this water is injected into the bottles to sterilize the interiors of said bottles as they pass through the apparatus.

Located within the housing A at the top thereof is a plurality of supporting bars 23 arranged transversely of the apparatus, said bars 23 being provided with horizontal supporting flanges 23'. Supported by the horizontal flanges of the bars 23 is a plurality of water receptacles, or pans, said pans being designated by the reference characters 24, 25, 26 and 27. By referring to Fig. I, it will be noted that the pans 24, 25, 26 and 27 are entirely separate and distinct from each other so that liquid which is introduced into one of said pans will not find its way directly from said pan into another of the pans. The pans 24, 25, 26 and 27 comprise each a bottom wall and upwardly extended side and end walls, and as is shown in Fig. I, adjacent walls of contiguous pans are spaced apart from each other and portions 23" of the bars 23 which aid in supporting said pans are interposed between said spaced apart walls.

28 designates a pump which is preferably composed of three sections, each of which is entirely separate from the other and contains separate pumping mechanism. The various sections of the pump 28 are designated by the reference characters 29, 30 and 31 in Fig. I. 32 designates the inlet pipe of the pump section 29, said inlet pipe being extended through the wall of the compartment 4 of the tank 1 and into the interior of said compartment. 33 designates the discharge pipe of the pump section 29, said discharge pipe being extended upwardly to a point immediately below the top wall of the housing A. As has already been stated, the adjacent walls of the water pans 24 and 25 are spaced apart slightly and arranged above said spaced apart walls is a pipe 34 which extends transversely of the housing A, said pipe being provided with rows of perforations 35. The rows of perforations 35 extend longitudinally of the pipe 34, the perforations of one row of perforations being so arranged that any liquid which is discharged therethrough will be directed toward the water pan 24, and the perforations of the other row of perforations being so arranged that liquid discharged therethrough will be directed toward the water pan 25. 36 designates a baffling device comprising an elongated plate having the approximate cross sectional shape of an inverted letter U, said baffling device being so arranged that the legs thereof straddle the pipe 34 and with one leg of said baffling device extended into the water pan 24 while the other leg of said baffling device extends into the water pan 25. The U-shaped plate comprising the baffling device 36 is approximately the same length as the inside dimension 130

- sion of the water pans 24 and 25 measured transversely of the housing A, and the length of the rows of perforations 35 in the pipe 34 is approximately the same length 5 as said baffling device. The discharge pipe 33 of the pump section 29 connects said pump section with the pipe 34, so that any liquid which is forced through the discharge pipe 33 will pass into the pipe 34 and be 10 discharged through the apertures 35, and because there are two rows of apertures in said pipe the body of liquid passing through the pipe 34 will be divided, some of said liquid being discharged against one leg of the baffling device and finding its way into the water pan 24, while another portion of said liquid will be discharged against the other leg of the baffling device and will find its way into the water pan 25.
- 15 37 is an inlet pipe leading to the pump section 30, said inlet pipe being extended through a wall of the compartment 5 of the tank 1 and into the interior of said compartment. Associated with the pump section 30 is a discharge pipe 38 which communicates with a pipe 39 arranged transversely of the housing A immediately above the adjacent spaced apart walls of the water pans 25 and 26. The pipe 39 is provided with a pair of rows of perforations 40, the perforations of one row of perforations being so arranged that liquid discharged therethrough will be directed toward the water pan 25, while the perforations at 20 the other row of perforations are so arranged that liquid discharged therethrough will be directed toward the water pan 26. 41 designates a baffling device similar to the baffling device associated with the pipe 34, said baffling device 41 being approximately U-shaped in cross section and having oppositely disposed legs, one of which is extended into the water pan 25 while the other thereof extends into the water pan 26. The inside dimension of the water pans 25 and 26 measured transversely of the housing A, the length of the baffling device 41, and the length of the rows of perforations 40 are approximately the same, 25 and because of this arrangement any liquid which is discharged through the apertures 40 will strike the legs of the baffling device 41 and will find its way into the pans 25 and 26. In view of this arrangement the liquid passing through the pipe 39 is divided, approximately one-half of said liquid being discharged into the water pan 25 and the other half being discharged into the water pan 26.
- 30 42 designates an intake pipe which is associated with the pump section 31, said intake pipe being extended through a wall of the compartment 6 of the tank 1 and into the interior of said compartment. Associated 35 with the pump section 31 is a discharge pipe 43 which is in communication with a pipe 44 arranged transversely of the housing A. The pipe 44 is located immediately above the spaced apart walls of the water pans 26 and 27, and said pipe 44 is provided with a pair of rows of perforations 45. The perforations of one of the rows of perforations are so arranged that liquid discharged therethrough will be directed toward the water pan 26 while the perforations of the other row of perforations are so arranged that liquid discharged therethrough will be directed toward the water pan 27. 44' designates a baffling device similar to the baffling devices 36 and 41 already described, 40 said baffling device 44' being approximately U-shaped in cross section and having oppositely disposed legs, one of which is extended into the water pan 26 and the other of which extends into the water pan 27. 45 The length of the baffling device 44' and the length of the rows of perforations are approximately the same as the inside dimension of the pans 26 and 27 measured transversely of the housing A, and as a result of this arrangement liquid which passes through the pipe 44 will be divided and a portion of said liquid will be discharged through one row of apertures 45 against one leg of the baffling device 44', thus finding 50 its way into the water pan 26, while another portion of said body of liquid will be discharged through the other row of perforations against the other leg of the baffling device and will find its way into the water 55 pan 27.
- 55 Located within the water pan 27 is a partition 46 which provides said water pan with a relatively small compartment 27'. Arranged immediately above the partition 46 is a pipe 47 arranged transversely of the housing A, said pipe 47 being provided with rows of perforations 48. The perforations of one of the rows of perforations formed in the pipe 47 are so arranged that liquid passing therethrough will be directed toward the main compartment of the water pan 27, while liquid passing through the perforations of the other row of perforations will be discharged toward the compartment 27'. 60 105 110 115 120 125 130
- 49 designates a baffling device which is approximately U-shaped in cross section and having oppositely disposed legs, one of which is extended into the main compartment of the water pan 27 while the other extends into the compartment 27' of said water pan 27. 50 designates a conductor which is in communication with the pipe 47, said conductor being adapted to conduct liquid to said pipe 47, and because of the arrangement of the perforations 48 and baffling device 49 approximately one-half of the liquid which passes through the pipe 47 will be discharged against one of the legs of the baffling device and will pass into the

main compartment of the water pan 27, while the other half of said liquid will be discharged against the other leg of said baffling device and will pass into the relatively small compartment 27' within the pan 27.

By referring to Fig. I it will be noted that the bottom walls of the mixing receptacles formed by the various water pans are provided with groups of perforations 51. It will also be noted by referring to the view mentioned that each of the water pans is provided with overflow notches 52, said overflow notches being formed in the opposite side walls of said water pans at the top edges thereof, as shown in Fig. II. The overflow notches formed in the walls of the water pan 25 are located immediately above the partition 2 which divides the compartments 4 and 5 of the tank 1, and the overflow notches formed in the walls of the water pan 26 are immediately above the partition 2 which divides the compartments 5 and 6 of said tank 1, and to divide the streams of water passing through said notches so that portions of each stream will be introduced into adjacent compartments, I arrange water-shedding devices 52' adjacent to said overflow notches. These water-shedding devices comprise each an inverted V-shaped plate and each of said V-shaped plates is arranged with its apex at the approximate center of the associated notch, as shown in Fig. II. By this arrangement the streams of water passing through the overflow notches will be divided, portions of said streams passing down the oppositely inclined walls of said water-shedding devices and being deflected to opposite sides of the partitions 2.

When the apparatus shown in the drawing is about to be placed in operation, steam is passed through the steam pipes 8, 10, 12 and 13 and said steam escapes through the perforations in said pipes into the liquid within the compartments 3, 4, 5 and 6. This steam is permitted to escape into said compartments until the liquid within the compartment 3 reaches the approximate temperature of 170°, the liquid within the compartment 4 reaches the approximate temperature of 140°, the liquid within the compartment 5 reaches the approximate temperature of 110°, and the liquid within the compartment 6 reaches the approximate temperature of 80°, and for the sake of clearness I have indicated these temperatures in Fig. I of the drawing. When the bodies of liquid reach the temperatures indicated the apparatus is ready to be placed in operation.

The bottles pass from the bottle-conveying mechanism G into the bottle holders C and begin their passage through the apparatus, the movement of said bottles being either continuous or intermittent, and when

said bottles reach the injectors 15 water is injected forcibly into said bottles by said injectors to wash the interiors thereof. The water which is forced into the interiors of the bottles is drawn from within the compartment 3 by the pump P, said pump placing said water under pressure. It is therefore apparent that the interiors of the bottles are washed with water at a temperature of approximately 170°. The bottles next pass over the injectors 21 associated with the conductors 20 and water from an outside source is injected into said bottles to sterilize said bottles, this water being at a temperature of between 180° and 200°. It is apparent, therefore, that when the bottles pass from the injectors 21 they are quite hot.

Water from within the compartment 4 is drawn therefrom by the pump section 29 and some of this water is introduced into the water pan 24. The bottom wall of the water pan is provided with groups of discharge apertures and therefore, as the bottles pass beneath these groups of apertures, water at a temperature of 140° will be showered on said bottles whereby the temperature of the bottles is reduced to approximately that temperature.

Water from within the compartment 5 is drawn therefrom by the pump section 30 and some of this water is introduced into the water pan 25. This water is at a temperature of approximately 110°, but it will be remembered that some of the water pumped from the compartment 4, the temperature of which is approximately 140°, is also being introduced into the water pan 25. The result of this, therefore, is that the two streams of water of different temperatures are merged to produce an elongated body of water the temperature of which varies gradually from a temperature of approximately 135° at one end of the water pan to a temperature of approximately 115° at the opposite end thereof. The bottom wall of the water pan 25 is provided with groups of discharge apertures spaced longitudinally of said water pan, and therefore as the bottles pass beneath said water pan said bottles encounter successive showers of water, each of which is slightly cooler than the preceding shower of water.

Water from the compartment 6 is pumped into the water pan 26, this water being at a temperature of approximately 80°, and said water flows toward and merges with a stream of water being pumped into the water pan 26 at the opposite end thereof, the last mentioned water coming from the compartment 5 and being approximately 110°. Here again the result will be that an elongated body of water will be produced the temperature of which gradually varies from a temperature of approximately 105° at one of its ends to a temperature of approximately 130°.

85° at its opposite end. The water within the water pan 26 will escape through the groups of discharge apertures in the bottom wall thereof, and as a result the bottles moving through the apparatus here also will encounter successive showers of water each of which is slightly cooler than the preceding shower of water.

In like manner water at a temperature of approximately 80° is pumped from the compartment 6 into the water pan 27 at one end thereof, and water from an outside source at a temperature of approximately 55° is introduced into said pan 27 at the opposite end thereof. These two streams of water flow toward each other and merge, the result being that an elongated body of water is produced the temperature of which gradually varies, the temperature of said body of water being approximately 75° at one end and 60° at the opposite end thereof. Also, this body of water is discharged through the apertures in the bottom wall of the water pan and therefore the bottles encounter showers of water each of which is slightly cooler than the preceding shower of water.

Finally the water which is introduced into compartment 27' by the pipe 47 is showered down on the bottles as they pass beneath the apertures in the bottom wall of said compartment 27', further reducing the temperature of the bottles to approximately 55°. It is apparent, therefore, that the temperature of the bottles or other articles is gradually reduced as they pass through the apparatus so that when they are finally discharged from the apparatus they may be immediately filled with relatively cold liquid without danger of cracking said bottles.

As already stated herein, the temperatures of the liquid within the compartments 3 and 4 are maintained uniform by thermostatically controlled valves which automatically admit steam thereto. However, there is no need for the introduction of steam into the compartments 5 and 6 after the temperature of the bodies of water therein have been brought to the proper point when the device is being placed in operation, due to the fact that water at a temperature of approximately 120° is being introduced into the compartment 5 to maintain the water therein at a temperature of approximately 110° while water at a temperature of approximately 90° is being introduced into the compartment 6 to maintain the water therein at a temperature of approximately 80°.

In addition to this the water will take up some of the heat from the bottles as said water is showered over said bottles, so that the water which pours back into the compartments will be slightly hotter than it was when said water passed through the discharge apertures in the bottom walls of the

water pans, although this additional heat of the water will be balanced by cooler water flowing through the overflow apertures 7 and by the cool water flowing into the compartment 6 from the compartment 27' of the receptacle 27. In Fig. I, I have indicated the approximate temperatures of the water issuing from the groups of apertures formed in the bottom walls of the water pans.

To prevent solid matter from passing through the inlet pipes 32, 37 and 42 to the pump sections I provide the open end of each of said pipes with a suitable screen. By merely varying the delivery of the coolest water to the pipe 47 it is apparent that the final temperature and all intermediate temperatures may be varied.

There is a constant flow of water into the apparatus through the pipe 47 and it is, of course, necessary to provide some means for an equal amount of water to escape from the apparatus. I therefore provide the compartment 4 with an overflow pipe 60 and permit water from the compartment 6 to overflow into the compartment 5 through the overflow aperture 7 in the partition between said compartments. Also, water from the compartment 5 flows through the overflow aperture 7 in the partition 2 between the compartments 4 and 5 and excess water within the compartment 4 is permitted to overflow therefrom through the overflow pipe 60. It is apparent that in this way the same water is used for successive operations and a great saving is therefore realized in the amount of water used.

61 designates an overflow pipe associated with the compartment 3 through which excessive water placed therein through the operation of the sterilizing ejectors 21 passes from said compartment.

I claim:

1. An apparatus for changing the temperature of articles comprising a spraying element including a mixing receptacle having a plurality of separated inlets through which a plurality of streams of liquid of different temperatures are introduced to produce a liquid mixture having different temperatures between said inlets, an element for supporting the articles below the first mentioned element, the mixing receptacle being provided with discharge apertures through which liquid is discharged on the articles, said discharge apertures being between said separated inlets and spaced from each other, and one of said elements being movable with respect to the other.

2. An apparatus for changing the temperature of articles comprising a mixing receptacle having separated inlets at opposite sides through which a plurality of streams of liquid of different temperatures are introduced to produce a liquid mixture having different temperatures between said inlets,

and a traveling support for the articles arranged below said mixing receptacle, said mixing receptacle being provided with groups of discharge apertures through which the mixed liquid is successively discharged on the articles as said articles are moved relative to said mixing receptacle by said traveling support, and said groups of apertures being between said inlets and spaced from each other.

3. An apparatus for changing the temperature of articles comprising a spraying element including a mixing receptacle having a plurality of separated inlets through which a plurality of streams of liquid of different temperatures are introduced to produce a liquid mixture having different temperatures between said inlets, an element for supporting the articles below the first mentioned element, the mixing receptacle being provided with discharge apertures through which liquid is discharged on the articles, said discharge apertures being between said separated inlets and spaced from each other, and one of said elements being movable with respect to the other, compartments located below different portions of said mixing receptacle to receive the liquid discharged from said discharge apertures, and means whereby the liquid is delivered from said compartments to the respective inlets to continue the delivery through said inlets.

4. In an apparatus for changing the temperature of articles, a plurality of separated mixing receptacles each having separated inlets through which streams of liquid at different temperatures are introduced to produce liquid mixtures having different temperatures between said inlets, a traveling support for the articles below said mixing receptacles, each of said mixing receptacles being provided with discharge apertures through which the mixed liquid is discharged onto the articles, said discharge apertures being between said separated inlets and spaced from each other, separated compartments located below different portions of the mixing receptacles to receive different portions of the mixture discharged from said discharge apertures, and means whereby liquid is transmitted from said compartments to the respective inlets.

5. In an apparatus for changing the temperature of articles, a plurality of separated

mixing receptacles each having separated inlets through which streams of liquid at different temperatures are introduced to produce liquid mixtures having different temperatures between said inlets, a traveling support for the articles below said mixing receptacles, each of said mixing receptacles being provided with discharge apertures through which the mixed liquid is discharged onto the articles, said discharge apertures being between said separated inlets and spaced from each other, separated compartments located below different portions of the mixing receptacles to receive different portions of the mixture discharged from said discharge apertures, and means whereby liquid is transmitted from said compartments to the respective inlets, said means including a single conductor through which liquid is returned from one of said compartments to two of said mixing receptacles.

6. An apparatus for changing the temperature of articles comprising a spraying element including a mixing receptacle having a plurality of separated inlets through which a plurality of streams of liquid of different temperatures are introduced to produce a liquid mixture having different temperatures between said inlets, an element for supporting the articles below the first mentioned element, the mixing receptacle being provided with discharge apertures through which liquid is discharged on the articles, said discharge apertures being between said separated inlets and spaced from each other, and one of said elements being movable with respect to the other, compartments located below different portions of said mixing receptacle to receive the liquid discharged from said discharge apertures, and means whereby the liquid is delivered from said compartment to the respective inlets to continue the delivery through said inlets, one of said mixing receptacles being provided with an overflow outlet between its separated inlets, and a deflecting member at said outlet whereby the overflowing liquid is divided, said deflecting member having oppositely disposed portions located above two of said compartments to direct the overflowing liquid into said two compartments.

In testimony that I claim the foregoing I hereunto affix my signature.

JAMES L. HEROLD.
